POWER HOIST

Charles R. Smith, Chicago, Ill.

Application April 13, 1942, Serial No. 438,779

6 Claims. (Cl. 212—1)

This invention relates to improvements in power hoists and more particularly to traversing hoists adapted for builders' and roofers' use, although capable of a variety of other uses. This invention may be considered a further development of my co-pending application for Hoists, Ser. No. 343,805, filed July 3, 1940, now Patent No. 2,305,202, granted December 15, 1942.

One object of the invention is to provide a power hoist wherein the weight of the motor serves to substantially offset or counterbalance the weight of the load being raised thus avoiding an otherwise possible topheavy condition and contributing materially to safety in operation, the motor being mounted to the boom to swing with the load.

A further object is to provide a power hoist that may be started or stopped and its speed regulated, or the brakes applied by a single control cord, the brakes being automatically applied when the control lever is released.

A still further and very important object is to provide a power hoist wherein the sectional frame may be readily carried to and erected upon a point of considerable elevation by one man and the motor thereafter raised from the ground or other point below the frame to the roof or high point wholly under its own power and at all times under complete control of the operator, and there readily affixed to the frame in working position. The motors used in power hoists are of very considerable weight and ordinarily are quite difficult to raise to points above the ground without the use of derricks or the like, but in the present instance this condition is not found as the motor is adapted to be raised and lowered readily by its own power.

A still further object is to provide a power hoist of great lifting power that is of few parts, readily assembled and dismantled, rugged and durable in construction, positive and efficient in operation, that is automatic in many features, and that calls for but little attention and effort on the part of the operator.

With the foregoing and other objects in view the invention consists in the combination and arrangement of parts to be hereinafter fully described, pointed out in the claims and illustrated in the accompanying drawings which form a part of this patent, and in which—

Fig. 1 is a side view of the power hoist wherein the motor is shown as being raised under its own power from a position but recently upon the ground to that of the frame atop a building or like structure.

Fig. 2 is an enlarged fragmentary view of Fig. 1 showing the clutch lever or control lever and fuel control means, the lever and connections being shown in three positions.

Fig. 3 is a side view of the motor with its frame, an altered position being shown in dotted lines.

Fig. 4 is a vertical sectional view through Fig. 3, on the line 4—4, looking in the direction of the arrows.

Fig. 5 is a view in perspective of the brake bands and connections employed.

Fig. 6 is a detail vertical sectional view through a pulley employed.

Fig. 7 is a view in perspective of the sectional hoist frame.

Fig. 8 is an enlarged detail view in side elevation of an adjustable boom extension arm with the pulley and trip employed.

- Fig. 9 is a front view of Fig. 8 with the trip omitted, and
- Fig. 10 is a side view on a reduced scale of the complete hoist upon a roof, illustrating its application.

Like reference characters denote correspond-

Like reference characters denote corresponding parts throughout the several views.

The power hoist includes a sectional main frame substantially triangular in shape and composed of the base 1 and sides 2, 2 connected by

the brace 3 and provided with cross braces 4, 4. Arranged at the apex of the triangle is the socket 5 provided with a bracket 6 to which is pivotally secured the upper end of the leg or truss bar 1 that at its lower end carries a weight rest 8 to receive a weight 9 to anchor the frame.

Received in the upper end of the socket 5 is the downturned end of the boom 10 adapted to be moved substantially horizontally through an arc of 180 degrees or less, said boom being connected by a vertical brace 11 and the stem 12 of a head 13 to a boom brace 14 that has its inner end pivotally received in the socket 15 arranged upon the said brace 3, said head 13 being fast upon said boom inwardly from the free end thereof. The socket 15 carries a bracket 16 connected by a bar 17 to a collar 18 adjustably arranged upon said leg 7. The frame, leg and boom may be disconnected from each other when desired, as when shipping the hoist or when it is not in use. By adjusting the leg relative to the frame the latter may be caused to stand perpendicular or at an angle to the perpendicular.

The power unit includes a frame formed of two side members, each of which comprises two vertical tubular members 19 connected by a

brace 20 intermediate their ends and by front and rear tubes or bars 21, 22 at their lower ends and by a rear top bar 23. The lower ends of both side members are supported in angle pieces 24 that extend rearwardly therebeyond as at 25 as clearly shown in Figs. 1, 3 and 10. Stub shafts 26 carried by said angle pieces have the wheels 27 loose thereon. Arranged upon the upper ends of the said side members are the forwardly extending angle pieces 28 that converge at their forward extremities and are extended to form the tongue 29 provided at its forward end with an eye 30 to permit it to be drawn by a truck when desired. Spaced braces 31 connect said tongue to the lower front bar 21 of the unit.

Arranged atop the angle pieces 28 are the bearings 32 for the shaft 33 of the rope or cable drum 34 that has its central portion of greater diameter than the ends to which said central portion is tapered, so that the cable wound thereupon will be wound uniformly thereover. The drum 34 carries upon its ends the brake drums 36, 37 provided with the brake bands 38 connected by grips 39 to the control bar 40 the ends of which are journaled in bearings arranged upon said angle pieces 28, one end of said control bar being connected by link 41 and rod 42 to the control lever 43 loose upon said shaft 33.

Fast to one angle 28 is the cam 44 that is loose about said shaft 33 and that is adapted for engagement with the cam lugs 45 of the lever 43, said lever abutting the shaft nut 46. Loose upon shaft 33 is the clutch member 47 adapted when in engagement with the drum 36 to drive the rope drum 34 and shaft 33 movable longitudinally in bearings 32.

As shown in Fig. 2 the extreme right hand dotted line position of the lever 43 is its normal position. The clutch is running freely upon shaft 33 and the brakes are applied by brake band connections, the bands being tight upon the brake drums. In the full line or intermediate position of said lever the brakes are off or free and the clutch running free. In the left hand dotted line position of said lever the brakes are off and said lever through engagement of its cam lugs 45 with the cam face of cam 44 has moved the cable drum with brake drums longitudinally of shaft 33 into operating engagement with the clutch 47 which is connected by sprocket chain 48 with the sprocket gear of the shaft 49 of the motor 50 supported upon the frame bars 21, 22. This latter position of lever 43 is running position and just prior to it assuming this position the motor throttle 52 is opened wide, from idling position, by means of the throttle connection 51 connecting said throttle and lever. Connecting said clutch and brake drum is the expansion coil spring 53 that yieldingly retains said members in disengaged relation. The speed of the cable drum and consequently of the load is controlled by manipulation of lever 43 by the operator with said lever in running position.

Secured to one vertical side member 19 is a bracket 54 to which one end of a spring 55 is secured to connect same to a bell crank 56 fulcrumed to an angle 28, one arm of said bell crank being reduced and by said spring being yieldingly retained in engagement with a pin 57 carried at the end of lever 43 to retain the same in running position when desired.

Also engaging said bell crank is a chain 58 connecting same to a trip fork 59 mounted for pivotal movement to a bolt 60 connecting the sides of a substantially L-shaped boom exten-

sion 61, said sides being separated by spacer sleeves 61a about the connecting bolts, said trip fork normally resting upon a stop 62 upon said extension, said extension being adjustably secured 5 to the boom 10 and to the brace 14 by bolts 63 passing through the sides of said extension and upon opposite sides of said boom and brace. When in adjusted position the extension is rigid but when the bolts are removed the extension 10 may be adjusted relative to the boom and brace as may be desired and the bolts then replaced to lock the extension. A pulley 64 provided with a wheel hanger 65a is mounted at the free end of said boom extension and provided with a rope 15 guide 65 mounted to a floating hub 66 received within the pulley hub, said guide being adjustable to any desired position and then locked by bolt 67, two positions of said guide being shown in Figs. 8 and 10. When the hoist is operated 20 upon a roof or elevation a control cord 68 connected to lever 43 and passing over a sheave 69 that is carried by a bracket 70 depends therefrom.

The end of the control cord 68 terminates in a 25 loop 71. Depending from the angle 28 is a bracket 71 that carries a sheave 88 over which a cord 89 passes to the bell crank 56, the free end of said cord terminating in a loop 90. Detachably secured to the rear ends of the angles 28 and extending transversely of the motor frame is the inverted U-shaped bail 78, the free ends of the sides of which are bifurcated and bolted to the staples 79 of the motor frame. Carried centrally of the base of said bail is the staple 80 for engagement by the hook 81 carried at one end of the cable 82 that passes between the tines of the trip fork 59 and over the pulley 64 to the cable drum 34. An eye-bolt 83 welded to the base of the bail 78 in line with staple 80 is engaged by 40 chain 84 that passes through the staple 85, of tongue 29, also in line with staple 80, said chain being provided terminally with a hook 86.

The lever 43 is retained in normal position by the spring 73 having one end secured to tongue 45 29 and the opposite end to a bracket 74 depending from the control bar 40. When it is desired to raise the motor by its own power from a position upon the ground or below the roof to the sectional frame upon a roof 98, or like elevation, the hook 81 is placed in the staple 80 and the hook 86 is engaged with the chain 84 at the proper point to prevent vertical oscillation of the motor, the forked terminations of the sides of the bail 78 engaging with the staples 79 and angles 28 preventing lateral tilting of the motor which might otherwise occur as the cable 82 is wound back and forth over the cable drum as the lifting operation proceeds.

The hook 91 of ground cable 92 is now placed 60 in the loop 90 of cord 89. The operator upon the ground now manually moves the control lever 43 from normal to running position where it is retained by the bell crank 56 and connections and the ascent is started. As the cable 82 is wound upon the drum the motor is raised from the ground. As it moves upwardly to a point at which it will clear the roof and firewall the operator pulls upon the cord 92 from his position upon the ground. This causes cord 89 to disengage the bell crank from the lever 43 which moves 65 into normal position, disengaging the clutch, as the brakes are automatically set and the load halted. The load, with boom 10, is swung horizontally to bring the motor over the roof. The lever 43 is now manipulated to gently deposit the 70 75

motor upon the roof. The hook 81 is now removed from staple 80, the bail 78 and chain 84 removed and the motor is ready to be disposed upon and secured to the sectional frame. To do this the leg 7 and bar 17 are removed from this frame, the motor tilted to dotted line position, Fig. 3, and the sectional frame tilted rearwardly until the boom 10 is disposed in the channelled tongue 29, the leg 76 having been removed. The leg 7 and bar 17 are now again attached to the sectional frame which, with the motor, is moved to operating position and the tongue secured to the head 13, or said members 7, 17 may be again replaced after the frame and motor are in operative position.

In operative position the channel-shaped tongue 29 of the motor frame receives or fits down over and upon the boom 10 with a thickened or reinforced portion 99 of said tongue resting upon the socket 5 at which point the greatest portion of the weight of the motor is borne, the forward end of said tongue fitting snugly over the head 13, a pin 100 being then passed through a perforation in said tongue that registers with a perforation 93 in said head and the motor and frame are firmly secured in operative position. To lower the motor again, when desired, the pin 100 is withdrawn and the motor manually held in place while leg 7 and bar 17 and the motor let down upon the wheels 27. The leg 7 and bar 17 of the sectional frame may be replaced and the motor may again be connected to its lifting gearing and lowered. The boom extension, previously described, serves among other things to permit moving the motor with its frame over a high or wide fire wall 98a.

Detachably secured to the tongue 29 by a pin 75 is a sectional telescoping leg 76, the sections being normally connected together in full extended position by a pin 76a, the lower leg section being provided with a perforation 76b to receive said pin 76a when the sections are partially telescoped to shorten the leg. The topmost end of the leg is square to snugly fit the channelled tongue while the lower end is provided with a cross bar 77 disposed upon the ground. When the motor is used without the sectional frame it rests upon the wheels 27, leg 76 in full extended position and bar 77. To lift very heavy loads it is operated without the wheels, the wheels being removed while the motor frame is tilted rearwardly into the dotted line position, Fig. 3. The frame bars 21, 22 now rest upon the ground, the leg 76 having been shortened as previously described. Planks or boards 101 are then placed upon the bar 77 and frame bars 21, 22 and weights placed thereupon to anchor the machine in position.

When the motor is used in position upon the sectional supporting frame the leg 76 is disconnected from the tongue and weights 9, 103, or either of them, are placed in position as shown in Figs. 1 and 10. To raise a load 94 by its bail 95 the hook 81 is engaged therewith, the cable 82 being wound upon the cable drum. To raise a very heavy load the back gear or tackle 96 is employed, the hook 81 being secured to a staple 97 secured to the end of the boom 10. The load is now somewhat more slowly but readily raised. From the staple 97 the cable passes about the sheave of the tackle, through the trip 59 and over pulley 64 to the cable drum. A collar 71 upon cable 82 contacts and raises the trip fork 59 when the load 94 is lifted to a certain maximum point.

What is claimed is:

1. In a power hoist, a frame, a motor carried thereby, a cable drum carried by said frame driven by said motor, a pulley, a cable upon said drum passing over said pulley, an inverted U-shaped bail having its ends secured to opposite sides of said frame, a staple disposed centrally of the base of said bail engaged by said cable, an eyebolt disposed centrally of the base of said bail, a second staple carried by said frame in line with said eyebolt, a chain connecting said eyebolt and passing through said second staple, and a hook carried by said chain for selective engagement with the links thereof.
2. In a power hoist, a frame having a tongue, a motor carried by said frame, a cable drum carried by said frame and driven by said motor, a pulley, a cable upon said drum passing over said pulley, an inverted U-shaped bail having its ends secured to opposite sides of said frame, a staple disposed centrally of the base of said bail engaged by said cable, an eyebolt disposed centrally of the base of said bail, a second staple carried by said tongue, a chain connecting said eyebolt and passing through said second staple, said eyebolt and staples being disposed in a common plane, and a hook carried by said chain engaging a link thereof.
3. In a power hoist, a frame including a boom, a cable drum, a clutch therefor, a motor connected thereto, a second frame carrying said cable drum and motor mounted to said first named frame, brakes for said cable drum, a lever for said clutch, means connecting said lever and brakes for yieldingly retaining said lever in normal position and applying said brakes, a bell crank carried by said second frame engaging said lever in running position to releasably anchor same, a pull cord for said bell crank, a pulley carried by said boom, and a cable upon said drum passing about said pulley.
4. In a power hoist, a frame including a boom, a cable drum, a motor connected thereto, a second frame carrying said cable drum and motor and mounted to said first named frame, a control lever for said cable drum, an extension arm adjustably carried by said boom, a trip fork carried by said extension arm, a rest for said trip fork carried by said extension arm, a pulley carried by said extension arm, a cable upon said drum passing about said pulley, a trip collar carried by said cable, and connection between said trip fork and control lever.
5. In a power hoist, a frame including a swinging boom, a cable drum associated therewith, an extension arm adjustably secured to said boom, a pulley carried by said extension arm, a cable guide for said pulley, a motor for said cable drum, a trip fork carried by said extension arm in line with said cable guide, a trip fork rest carried by said extension arm, a cable upon said drum passing about said pulley through said cable guide and trip fork, connection between said trip fork and motor, and a trip collar carried by said cable.
6. In a power hoist, a swinging boom, a support therefor, a pulley carried by said boom, a cable drum, a motor therefor, a frame carrying said cable drum and motor for detachable application to said boom, and a cable upon said drum passing about said pulley for connection to said frame in one position thereof and for connection to a load in another position thereof relative to said boom.
